DRIVING ARRANGEMENT AT CIGAR
MACHINES

Karl Erik Granstedt, Stockholm, Sweden, assignor
to Aktiebolaget Formator, Stockholm, Sweden,
a joint-stock company of Sweden

Application November 20, 1931, Serial No. 576,392
In Sweden December 1, 1930

6 Claims. (Cl. 131—39)

The present invention refers to a driving device for smaller working members in ordinary cigar machines, such as members for smoothing out the wrapper at the head of cigars, rotating knives for cuttings in the wrapper, etc. Such devices have hitherto been driven either by belt transmissions or by special small electric motors, which causes the disadvantage that the devices became rather expensive and too voluminous. 5 Besides, it was only with great difficulties that the speed of said devices could be regulated in order to conform to different conditions and occasions. Finally, the driving device has not been sufficiently yielding, which sometimes has a bad 10 influence on the function of the members aforesaid.

According to the present invention said disadvantages are removed by using a motor in the shape of a propeller or a fan-like body as driving device for one or several of the members mentioned, which motor is brought in rotation by means of currents of air or other gaseous means caused by suction or pressure. Such a motor will in the following be called a windmotor. 20

As is well known, there is in ordinary cigar machines an arrangement for producing suction, used for sucking the wrapper to the cutting pad and to the device transporting the wrapper from the cutting pad to the rolling device. According to 25 a preferred execution of the invention the suction arrangement already existing is used for the driving of the windmotors. This imports a simplification of the design of the machine and a rather considerable saving of expenses. The speed of 30 the windmotors and consequently the speed of the members driven by the same can easily be regulated by means of adjustable shutters arranged in the suction tube. As the suction producing arrangement works independent of the 35 other movable parts of the cigar machine, the special members above mentioned can be driven independently whether the machine is in operation or not. This imparts a great advantage, as for instance the smoothing out of defective cigar 40 ends has hitherto often had to be made by hand, when the cigar machine is not in operation.

A preferred embodiment of the invention is shown on the enclosed drawings.

Fig. 1 shows partly in section a tube with three 50 members driven by windmotors, and Fig. 2 shows the same device seen from above and in somewhat larger scale.

On the frame of the cigar machine is attached a bracket 2 carrying a tube 3, the interior 19 of 55 which is connected to a suction source not shown

on the drawings. According to the shown embodiment, windmotors are placed in the free end of the tube and in two side nozzles 30 and 31, which motors are directly connected to one working member each. The device at the one nozzle 30 consists of a rotating knife arrangement 18, whilst the device at the other nozzle 31, as well as the device at the end of the tube consists of a smoothing arrangement for the cigar tips. The first of these smoothing means is not axially 10 movable and is mainly intended to be used when the cigar machine is not in operation. The other smoothing means at the free end of the tube is, on the contrary, axially movable, and such movement is obtained by the means of members guided 15 by the driving device of the cigar machine, and arranged in the following manner:

On the under side of the support plate 1 is fixed a bracket 4 carrying a shaft 6 driven by the driving device of the cigar machine. On said shaft is 20 fixed a disc with a cam-shaped groove 7, in which a roller 8 is sliding, and which is rotatably journaled on a pin 9, attached to the one arm of an angular lever 5. This angular lever 5 is rotatably journaled on a pin 22, carried by the support 23 25 attached at the upper side of the support plate 1. The free—upper—end of the second arm of the angular lever has the shape of a fork, the shanks of which are provided with long grooves cooperating with pins 26 attached to bushings 11, enclosing a part on a shaft 13, which has a smaller diameter than the other parts of said shaft. A windmotor 14 is attached to the inner end of the shaft within the tube 3, whilst a smoothing member, called a headformer 10, is fixed on the outer 30 end of the shaft. The cigar head to be smoothed out is marked 24. The shaft 13 is rotatably journaled in a bearing 25, attached to the inside of the tube 3 by means of spokes 12. The design of the smoothing means arranged at one of the side 35 nozzles 31 is mainly corresponding to the one described above. The rotatably journaled shaft 13^a is, however, not axially movable, as such movement is prevented by the flanges 20 and 21 attached on the shaft and resting against both sides 40 of the bearing 25. This smoothing arrangement is intended to be used as well when the cigar machine is in operation as when it is at a standstill, and in the latter case especially for a second treatment of defective heads. The first mentioned 45 smoothing arrangement functions, on the contrary, in such a relation to the other operations of the cigar machine that an automatic smoothing out of the heads of the cigars is obtained.

The third of the devices shown on the drawings, 55

namely the rotating knife arrangement 18, arranged at the side nozzle 30, consists of knives 18 attached to the outer end of the shaft 13^a, on the inner end of which the windmotor 14 is fixed. 5 This knife shaft 13^a is rotatably journaled in the bearing 25 and is prevented by means of flanges on the shaft resting against both sides of the bearing 25 from moving axially. Inside the windmotor 14 of the member 18 is a regulating shutter 16 arranged in the tube nozzle 30, and a similar 10 regulating shutter 16 is arranged in the part of the tube 3 lying between the two nozzles 30 and 31. Each of the shutters consists of a round disc 16, the diameter of which is as large as the inner diameter of the tube, and which is provided with pins 27 and 17, by the means of which it is rotatably journaled in the walls of the tube. The upper pin 17 is lengthened outwards and bent in order to form a handle 17^a.

20 The object and the effect of the devices mentioned is the following.

By the air current or air currents produced by suction in the suction tube 3, the windmotors and consequently the two smoothing arrangements 25 and the knife arrangement are brought in rotary motion. When the smoothing arrangement 13, 10 placed at the end of the tube 3 is rotating, it also receives from the driving shaft 6 an axially reciprocating movement by means of the parts 7, 30 8, 9, 5, 26 and 11, so that when a cigar with its head 24 has been brought in known manner to the position shown on Fig. 1, the smoothing arrangement approaches the head of the cigar and stops finally in the position shown on Fig. 2, where 35 it forms the cigar end and then returns to give place for a new cigar. At the other smoothing arrangement, the cigar head is placed by hand into the head former 10.

The rotating knives 18 are adapted for making 40 a necessary cut in the wrapper, which for this reason is in a known way brought against the knives.

The speed of the windmotors can easily be regulated by means of the shutters which are turned 45 by hand around the pins. Thereby the cross section through which the air current is passing will be lessened or increased.

One shutter is placed in such a manner that the rotation of both the smoothing arrangements 50 can be regulated with the same. It is, of course,

also possible to have one shutter for each of the two smoothing arrangements.

For producing the suction (or pressure) a special apparatus may be used for each cigar machine, or else a common apparatus for several machines. 5

What I claim is:

1. In a cigar machine having a source of suction, a rotatable cigar header member, a suction conduit connected to said source of suction, and 10 an air-rotatable propeller arranged in said conduit and connected to said header member and driven by said source of suction.

2. In a cigar machine having a source of suction, an air-rotatable leaf cutting knife, a suction 15 conduit connected to said source of suction, and an air-rotatable propeller arranged in said conduit and connected to said knife and driven by said source of suction.

3. In a cigar machine having a source of suction, a rotatable header member, a suction conduit connected to said source of suction, an air-rotatable propeller arranged in said conduit and connected to said header member and driven by 20 said source of suction, and a mechanism for imparting axially reciprocating movements to said tool. 25

4. In a cigar wrapping machine having a source of suction, the combination with a rotatable wrapper handling tool of a suction conduit connected 30 to said source of suction, and an air-rotatable propeller arranged in said conduit and connected to said tool and driven by said source of suction.

5. In a cigar wrapping machine having a source of suction, the combination with a rotatable wrapper handling tool of a suction conduit connected 35 to said source of suction, said conduit having an aperture, and an air-rotatable propeller arranged in said aperture and connected to said tool and driven by said source of suction.

6. In a cigar wrapping machine having a source of suction, the combination with a rotatable wrapper handling tool of a suction tube connected to said source of suction, a rotatable shaft mounted axially of said tube and carrying said tool secured 45 to it, and an air-rotatable propeller arranged in said tube and secured to said shaft and driven by said source of suction.

KARL ERIK GRANSTEDT.
